ADJUSTABLE NOZZLE

Albert F. Albach, Frankfort-on-the-Main-Hochst,
and Franz Karger, Frankfort-on-the-Main-
Nied, Germany

Application February 8, 1939, Serial No. 255,350
In Germany May 11, 1938

1 Claim. (Cl. 299—145)

This invention relates to an adjustable nozzle designed primarily for use in connection with fire-hose, but it is to be understood that a nozzle in accordance with this invention is for employment for any other purpose for which it may be found applicable.

5 The invention has for its object to provide, in a manner as hereinafter set forth, a nozzle of the class referred to for producing a water spout of any desired size.

10 The invention has for a further object to provide, in a manner as hereinafter set forth, a nozzle of the class referred to for fire extinguishing purposes and for protection against gases.

15 The invention has for its further object to provide, in a manner as hereinafter set forth, a nozzle of such class by means of which it is possible to produce a more or less flat cone of water spray between the person handling the nozzle and a source of gases.

20 A further object of the invention is to provide, in a manner as hereinafter set forth, a nozzle of the class referred to for producing a water spout of the desired size, a water screen between the person handling the nozzle and a source of gases and with the water spout capable of being produced independently of the screen.

25 Further objects of the invention are to provide, in a manner as hereinafter set forth, a nozzle for use for fire extinguishing purposes which is simple in its construction, strong, durable, compact, expeditiously adjustable, conveniently handled, thoroughly efficient in its use for the purposes intended thereby, readily assembled, and comparatively inexpensive to manufacture.

30 Embodying the aforesaid objects and to others which may hereinafter appear, the invention consists of the novel construction, combination and arrangement of parts as will be more specifically referred to and illustrated in the accompanying drawings, wherein is shown an embodiment of the invention, but it is to be understood that changes, variations and modifications may be resorted to which fall within the scope of the invention as claimed.

35 In the drawings:

Figure 1 is a longitudinal sectional view of the nozzle when in closed position.

40 Figure 2 is a view similar to Figure 1 with the nozzle partly open and further showing in dotted lines to form a water spout and a water screen disposed in a direction leading therefrom.

45 Figure 3 is a side elevation of the nozzle.

50 Figure 4 is a view similar to Figure 1 with the nozzle completely open for discharge of a water

spout and closed to prevent the formation of a water screen, and

5 Figure 5 is a fragmentary view of the nozzle in longitudinal section and upon an enlarged scale.

The nozzle includes a body part 1, in the form 5 of a pipe of the desired length and diameter which has mounted on its inner end a coupling 2 for connecting body part 1, to a source of water supply. The body part 1 will be hereinafter referred to as a spout pipe.

10 The nozzle includes a tubular mouthpiece 3 having its inner face or inner wall formed of a tapered rear portion gradually decreasing in diameter outwardly and a tapered forward portion which also gradually decreases in diameter 15 outwardly. The said forward portion is of materially greater length than the said rear portion and terminates at the outer end of the mouthpiece. The said rear portion starts at the inner end of the mouthpiece and merges at its forward 20 end into the rear end of the said forward portion. The diameters of the said rear portion are greater than the diameters of the said forward portion.

15 The inner face or wall of the mouthpiece 3 25 serves as outlet for the spout pipe 1. The rear portion of the inner face of the mouthpiece 3 constitutes a frusto-hollow cone indicated at 4. The forward portion of the inner face of the mouthpiece 3 constitutes a frusto-hollow cone 30 indicated at 5. The cone 4 is upon a greater slant than the cone 5, this is due to the diameters of the said forward portion with respect to the diameters of the said rear portion.

20 Arranged at the outer end of the spout pipe 1 35 and encompassed by the mouthpiece 3 is a regulating element 5a, which is attached to pipe 1 by a plurality of wings 6. The regulator 5a consists of a forward solid cone 7, a rear solid cone 8 and an intermediate coupling part 9 of uniform 40 diameter. The cones 7, 8 are oppositely disposed and their bases merge into the coupling part 9. The cone 7 is of materially greater length or height than the cone 8, and preferably the length or height of cone 7 will be two and one-half 45 times greater than the length or height of cone 8. The cone 7 extends towards the outlet of mouthpiece 3. The cone 8 extends towards the spout pipe 1. The cones 7, 8 constitute regulators for the water spout discharged from mouthpiece 3. The wings 6 are integral with the cone 8 and are attached to the spout pipe 1 by the screws 10. The wings are streamlined in order to cause a minimum resistance to the flow of water through the nozzle. Revolubly mounted on 55

the spout pipe 1 is an adjuster in the form of an annular casing 13 having its inner face provided with female threads 12 in which the heads 11 of the screws 10 are positioned. The casing 13 at its forward end merges into the rear end of the mouthpiece 3. Attached to and encompassing the casing 13 is a regulating ring or sleeve 14. A packing 15 is interposed between the casing 13 and the spout pipe 1.

10 The nozzle includes a spray-diffuser comprising a circular flange 16 formed integral with the outer face of mouthpiece 3 at the inner end of the latter and a shiftable spray controlling collar 17 mounted on the casing 13. The flange 16 is formed with a sharp edge 18. The collar 17 is provided with a sharp edge 19, which encompasses the edge 18. The edges 18, 19 co-act to form a water discharging slit. The collar 17 carries a ring-like packing 20 acting to prevent the passage of water to the slit when the edges 18, 19 are in close relation.

20 The forward end surface of the collar 17 is formed with a cavity 21 having its bottom of dome-shape contour leading from edge 19 for the purpose of increasing the width of the slit and also to form a deflector for the water spray (Figure 2). The water is supplied to the slit provided by the edges 18, 19 through spaced rows 22, 23 of elongated spaced openings disposed circumferentially of the forward end terminal portion of the casing 13. The openings of one row are staggered with respect to the openings of the other row.

25 The collar 17 in proximity to its forward end has an annular peripheral groove in which is mounted a resilient ring 24 for gripping purposes when adjusting the collar 17. The outer diameter of ring 24 is larger than any other part of the nozzle. A flanged nut 24a revoluble and 30 slidable upon the casing 13 extends into the rear end of and threadedly engages with the inner face of the collar 17 for a purpose to be referred to.

35 As shown in Figures 1, 2 and 4 the spout pipe 1, in every position of the nozzle is arranged against the threads 12 and thus prevents the formation of water whirls.

40 By revolving the sleeve 14 it is possible to adjust the solid cones 1, 8 relative to the hollow cones 4, 5 to any position ranging from that shown in Figure 1, where the nozzle is shown completely closed to that shown in Figure 4 where the nozzle is completely open.

45 By shifting the collar 17, it is possible to change the width of the passage formed by the slit between the edges 18, 19, and which makes it possible to keep the pipe shaped water screen together or to change it to one of flat circular form.

50 The staggered position of the openings 22, 23 provides for a complete uniform supply of water to the slit formed between the edges 18, 19, and the water will be completely shut off to the slit by packing 20 when edges 18, 19 are arranged in close relation.

55 A packing 25 is interposed between the collar 17 and casing 13 and is engageable by the nut 24a for making tight the space between casing 13 and collar 17. If the nozzle happens to fall to the ground, or if it hits against a wall, the ring 24 will serve as a protection.

60 A water spout may be produced with or without the water spray screen, and the latter may be produced and regulated independently of the

former. The spout may be produced and regulated independently of producing the screen.

Owing to the design and arrangement of the regulating cones, it is possible to let out a water spout, even if the nozzle is only partly open; in such case the spout is given a very wide range. When the water is streaming out, the outgoing water is conducted and kept together by the slim hollow cone 5 as shown in Figure 4.

The structure as described and shown provides a water spout nozzle surrounded by an annular spray nozzle, by which it is possible to produce a more or less flat cone of water spray as a screen between the person handling the nozzle and the source of gases. With or without this spray feature it is possible, by means of the structure, to produce a water spout of any desired size, due to the fact that this invention has as an element thereof a regulator having a pair of solid cones for co-acting with a pair of hollow cones for the regulation of the water spout. The ratio between the heights of the solid cones is 1:2.5, the longest solid cone being situated toward the outlet of the nozzle. That one of the two hollow cones (into which reaches the longest of the solid cones which serves as a regulator) situated nearest the outlet is only slightly slanting, whereas the one situated further inside is more slanting. In shifting a solid cone from one position to another inside a hollow cone it is possible, on the one hand, to cut off completely the water spout, and, on the other hand, to regulate it so that a continuous stream of water is produced, which, when the nozzle is only slightly open, does not touch the inner wall of the nozzle, but, when the nozzle is completely open, is conducted along and kept together by this wall. The function of the piece connecting the two solid cones is to calm down the stream of water, evenly distributed at the inner wall, so that no whirls can occur when the water passes the outer solid cone.

65 The water screen is controlled by the collar 17 which co-acts with the flange on the mouthpiece to form the annular slit for passage of the water to form the screen and the flow of water through the slit may be shut off or regulated by this collar. In order to secure an absolutely even distribution of the water when it approaches this slit, and in order also to obtain a completely continuous and evenly cone-shaped water surface at the spray-diffusing nozzle the openings 22, 23 are provided and disposed in the manner aforesaid.

70 The spray-diffusing collar controls the water surface, guides the water screen when the spray-diffusing nozzle is completely open, and also regulates the angle of exit, as well as the degree of diffusion of the water screen. It is thus possible to obtain not only a completely even water screen, but also, by adjusting the angle of exit of the water, to change the original pipe-shaped spout to a water screen of flat circular form. The cavity closely joining the sharp edge of the spray diffusing collar also produces a certain whirling of the water, so that it is possible to obtain a very fine diffusion, which can repulse gases hitting the water screen, extinguish fire, and provide a complete protection for the person handling the nozzle.

75 What I claim is:

In a nozzle, a tubular body part adapted for connection at its rear end with a water supply, a regulating element disposed adjacent to the outer end of said body part and supported from

the latter, an adjustable casing encompassing said body part, a mouth piece integral at its rear end with the outer end of the casing and provided at its inner end with a laterally extending annular flange having a sharp edge portion, said casing being formed with slots spaced from the regulating element and disposed in proximity to said flange for the passage of water from said body part, a shiftable collar encompassing said 5 casing and having its forward end edge formed with an inwardly extending rearwardly directed curved surface terminating in a sharp edge por-

tion spaced from the inner face of the collar, said sharp edge portion of the collar coacting with the sharp edge portion of the flange to form a water discharging slit to provide a water shield, and a ring-like packing seated in said end edge 5 rearwardly of and in juxtaposition to the said sharp edge portion of the collar to arrest the passage of the water to said edge portions when the edge portions are disposed in close proximity.
